UNITED STATES PATENT OFFICE.

JAMES C. THOM, OF CHICAGO, ILLINOIS, ASSIGNOR TO COMBINATION MACHINE COMPANY, OF NEW YORK, N. Y., A CORPORATION OF DELAWARE.

SHEET-FEEDING METHOD AND MEANS.

1,425,350.

Specification of Letters Patent. Patented Aug. 8, 1922.

Application filed March 14, 1921. Serial No. 452,891.

To all whom it may concern:

Be it known that I, JAMES C. THOM, a citizen of the United States, and resident of Chicago, in the county of Cook and State 5 of Illinois, have invented certain new and useful Improvements in Sheet-Feeding Methods and Means, of which the following is a specification.

This invention relates to a method and 10 apparatus for feeding blanks or sheets and more particularly to a method and apparatus for successively feeding individual blanks or sheets, such as labels, for application to packets or containers and has particular reference to the provision of a method 15 and apparatus of the nature referred to, in which sheets or labels of varying dimensions may be individually fed from a stack or pile in an efficient manner and may be 20 fed in centered or registered relation for application to the packets or containers.

In the art of labeling packets or containers, a series of label blanks or sheets are placed in stack or pile formation, in a supply 25 magazine, the labels being fed individually from the supply stack either from the top or bottom thereof, the labels being then fed through an adhesive supplying station where the labels receive a coating of 30 adhesive and to a station where the adhesively coated labels are applied to the packets or containers. The pile or stack of labeled blanks which are fed from the magazine is obtained by cutting a stack of large 35 sheets having a plurality of label imprints on each sheet, such stack being cut into a plurality of piles of labels equal in number, as is apparent, to the number of label imprints on such large sheet.

40 In order to have each label properly centered in the supply magazine and properly fed in centered relation therefrom for proper registry with the packets or containers to which such labels are to be applied, it is requisite that all the labels should 45 have the same dimensions in width and length, guiding means, spaced such width or length in the magazines being required to guide the labels in the desired centered 50 and registered position. It has been found, however, practically impossible to attain this desired end, principally for the reason that it has been found impossible to cut all the labels to the same dimensions. It has 55 been found, for example, that after the cutting 60 operation the labels have varying widths or lengths. This has been found to be especially true with labels of relatively small dimensions such as are used for application to small packets or containers. 60 With such relatively small label blanks the percentage variation in the dimensions of the cut labels assumes relatively large proportions, this resulting in numerous defects 65 in label feeding.

One of the principal defects in label feeding resulting from this practical inability to obtain constant dimensioned labels in the cutting operation lies in the failure to obtain efficient selection of individual blanks 70 from the label stack. As referred to above, the labels are fed individually from the magazine for label coating and label application. This is usually accomplished by the provision of a picker operative for selecting 75 a label either from the top or bottom of the label stack, means being usually provided in the magazine for restraining label removal, such means functioning so as to permit only single sheets to be selected by the 80 picker and so as to prevent multiple sheet selection by such picker. Such means usually comprises lips or flanges overhanging in the path of label movement and cooperating with the labels for preventing such 85 multiple label selection or removal. The amount or degree of overhang of the restraining lips or flanges forms a very important consideration. Such restraining means, for example, should not provide too 90 large an overhang for the reason that too large an overhang will prevent, rather than restrain, label removal activity. All that has been found necessary for efficient label restraining activity is a very short over- 95 hanging lip or flange engaging the label edge. For illustration it may be suggested that if the point of a pin be ever so slightly bent, as by movement of the pin over a rough surface, the resulting minute hook or 100 overhang in the pin point is sufficient to grip the edge of a sheet for restraining movement thereof. It has been found, however, due to the variations in the dimensions of the labels used, that if a short lip or over- 105 hang be provided, although the labels of larger dimensions are effectively engaged and restrained, the labels of smaller dimensions will fail to be engaged by the protruding lips with the result that the picker will 110

remove a plurality of labels during selection activity, whereas a single label only should be selected. This is especially true where the labels are fed from the bottom of the stack and in such event when a label of relatively large size is selected, the following labels, if of smaller size, escape the restraining elements and fall through the magazine on the picker or selector, resulting in improper label feeding. If, to overcome this, a large overhang be supplied sufficient to reach the labels of all the varying dimensions, such large overhang, although properly functioning as respects the smaller size labels, will prevent rather than restrain removal by the picker of the larger size labels, this also resulting in improper label feeding. The provision of a method and means in which multiple label selection will be prevented and individual label selection facilitated is, therefore, an obvious desideratum.

Another principal defect resulting from the variation in dimensions of the cut labels lies in the failure to secure proper centering of all the labels in the magazine stack and the failure to obtain as a consequence properly registered labels as applied to the packages or containers. For the purpose of accommodating or receiving all of the labels, the dimensions of the magazine compartment or pocket should be as large or larger than the label of largest cut dimensions. In such a magazine pocket it has been found that the labels of smaller dimensions are subject to the liability of shifting to one side or of turning in the magazine within limits, this resulting in an improperly centered label in the magazine and a selection of such label by the picker in decentered position. With the labels fed to the containers in this decentered position the labels applied to the containers will be out of registry with the container walls, and where the container and label are both of small or narrow dimensions, an imperfect registry is conspicuously apparent. It has therefore been found desirable to provide a method and apparatus whereby such labels may be properly centered in the magazine and may be properly fed for label registration.

The principal objects of my invention therefore include, in addition to the provision of a method and means for feeding label blanks or sheets, the provision of such a method or means in which the blanks will be individually fed in an efficient manner; the provision of a method and means of this type in which any label of a stack of labels of varying dimensions may be individually selected in a facile manner, with the minimizing of multiple label selection or removal; the further provision of such means in which any such label of a stack of labels of varying dimensions may be properly cen-

tered in the supply magazine and properly fed for registry in label application; the still further provision of a novel form of label and novel guiding and centering means associated therewith and the provision of such method and means simple in structure and operation accomplishing the necessary functions in an efficient and facile manner.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention and in which—

Figure 1 is a perspective view of a stack of labels showing excised portions therein in registering relation to provide guide ways or channels.

Figure 2 is a plan view of apparatus used for obtaining the excised portions in the labels,

Figure 3 is a perspective view of a magazine compartment adapted for bottom feeding of labels and showing the guide means used for cooperation with the guiding channels in the labels,

Figure 4 is a perspective view of such magazine with the labels shown guided and supported therein,

Figure 5 is a view in detail of one of the guiding elements used in the magazine,

Figure 6 is a cross sectional view of a magazine adapted for multiple label feeding, parts being broken away,

Figure 7 is a plan view of the same,

Figures 8 to 11 are diagrammatic views of a label feeding apparatus showing the various steps during which the labels are centered in the magazine and fed in centered registry relation for label application to a container, and

Figure 12 is a perspective view of a container with a registered label thereon.

Before describing my apparatus and method in detail I will briefly state the principles underlying my invention and the operative steps I employ in providing for the label selection and registration above referred to. The labels, after being cut in pile or stack formation, are fed into a well or shaft, a series of oppositely disposed rotary cutters in the form of rotary saws being provided for excising portions of the labels in the edges thereof as the label stacks are fed through the said well or shaft. The labels, after this excising operation, are provided with a plurality of similar milled portions or saw kerfs, the registering saw kerfs of the superposed labels in the stack defining a way or channel adapted as a guide for subsequent label centering and registration. The depth of the milled portions or

saw kerfs is predetermined such that all the labels, irrespective of dimensions, are provided with such saw kerfs. This is effected by so arranging the rotary saws that the 5 distance (as measured along a line, for example, parallel to a width or length of the label) between the bottoms of saw kerfs in a label is less than the width of the label of smallest width in the stack, the distance be- 10 tween the bottoms of such saw kerfs being equal in each label and being of a predetermined constant value. The excised labels are then hand fed into a magazine provided with a plurality of vertically disposed guide 15 rods having a cross section preferably similar to the cross sectional configuration of the saw kerfs, the guide rods being spaced in the magazine a distance equal to the predetermined constant distance between the 20 saw kerf bottoms; the guide rods and the guide channels provided by the saw kerfs forming cooperating guiding elements for centering each label of the stack in the magazine, this cooperation permitting of regis- 25 try label feeding. Since each label irrespective of dimensions, is provided with excised portions, it will be evident that the guide rods will contact the edges of each 30 such label. I therefore further provide each guide rod at an end thereof with a slight overhanging lip or flange just sufficient to perform the label restraining function, it being evident that such slight overhang will 35 contact and engage each label of the stack whether such label be of a maximum or minimum width. In this manner each label may be effectively restrained against movement, this eliminating multiple label removal, while at the same time permitting with fa- 40 cility single label selection by the label picker above referred to. The labels, after being individually removed from the magazine by the picker, are then fed in centered relation in any desired manner to a label 45 applying station, and the label is there applied to a packet or container in registered position thereon.

Referring to Figure 1 of the drawings, the label stack 20 comprises a series of super- 50 imposed labels L, the widths or lengths of these labels varying in dimensions, as hereinbefore referred to. Each of the labels L is provided preferably with a plurality of excised portions 21, these excised or cut out 55 portions of the superposed labels registering, as shown in Figure 1 of the drawings, such registration providing elongated channels or ways in the stack, these channels being adapted for cooperation with 60 guide means for the guiding and centering of the stacks of labels in the further use thereof. The excised portions 21 are provided in the edges of the labels and may be provided in any spaced manner desired. 65 The preferred arrangement is shown in

Figure 1, in which the cut out portions 21 are arranged in opposed relationship, each label being thus provided with a plurality of sets of oppositely positioned cut out portions. The cut out portions 21 are milled 70 to a predetermined depth in the labels, such that the distance (as measured, for example, between the bottoms of a set of cut out portions 21, such distance being designated in Figure 1 as d) is less than the width of 75 the label of smallest width in the stack. Looked at from another aspect, the milled portions 21 are cut to such a depth such that each label, irrespective of width or length, will be provided with excised portions. It 80 therefore follows that each label, whether of maximum or minimum width or length, will be provided with a body portion such as d equal in every such label. Although I have shown the excised portions as arranged 85 in opposed relation, it will be apparent that other means of arranging the excised portions may be provided, the principle involved being that each label be provided with a milled portion such as 21 to coop- 90 erate with other means hereinbelow described in detail for label centering and registration.

Referring to Figure 2 of the drawings, I have shown a means which may be used in 95 providing the milled or cut out portions 21 in the stack of labels 20. Such means may comprise a well or shaft 22, bounded by walls 23, the walls 23 being provided with a plurality of spaced slits or apertures 24, in 100 which rotate a plurality of spaced rotary cutters or saws 25, the saws 25 extending into the well 22 a predetermined distance, as clearly shown in Figure 2 of the drawings. The rotary saws 25 are so spacedly 105 mounted as to provide the spaced milled portions or saw kerfs 21 in a label stack 20, as shown in Figure 1. The cutters 25 are mounted on a plurality of shafts 26, journaled in a plurality of standards 27, mount- 110 ed on the base plate 28; the shafts 26 being provided with intermeshing bevel gears 29 for the operation of all the shafts in unison, one of the shafts 26 being connected to motive power (not shown) for the purpose of 115 operating the rotary saws. The end shafts 26 are each provided with opposed thrust collars 30 for the purpose of preventing endwise movement of these shafts in order to keep the end rotary saws 25 in exact cen- 120 tered position. The intermediate shafts 26 are each provided with thrust nuts 31 also functioning to prevent endwise movement of these shafts and to maintain the rotary saws 25 on these shafts in properly cen- 125 tered position. The rotary cutters or saws may be arranged or spaced in any desired manner, the preferred arrangement being shown in the said Figure 2, this arrangement comprising the mounting of the saws 130

in opposed relation to provide the saw kerfs in similar opposed relation, the distance between any two opposed rotary cutters being equal to d and thus being equal to the distance d between the bottoms of saw kerf 21. The labels, after they are obtained from the cutting of a large sheet containing the plurality of imprints, are fed into the shaft or well 22 and are fed in such shaft in centered position, the opposingly rotating saws 25 aiding in centering any given stack of labels in the said shaft 22. As a result of this centered feeding of the labels through the shaft 22, each label is provided with similar excised portions similarly arranged thereon, the bottoms of these excised portions being substantially a constant distance from a longitudinal medial line of each label.

The excised labels are intended for use with a supply magazine adapted either for bottom or top feeding. In Figure 3 of the drawings I show a magazine adapted for bottom label feeding. Said magazine consists of a compartment 32, bounded preferably by the walls 33, the distance between opposing walls 33 being large enough to accommodate the largest width of label obtained by the prior cutting operation. The magazine is provided also with a plurality of spaced guiding elements 34, these guiding elements having preferably a cross sectional configuration similar to the cross sectional contour of the excised portions 21 of the labels. The guiding elements 34 in the form preferably of guide rods, are arranged in the compartment 32 similar to the spaced arrangement of the saw kerfs 21 in the labels. Furthermore, the distance between any two opposed guide rods, 34 is made substantially equal to the distance between the bottoms of a set of opposed saw kerfs 21, this distance being designated also as d in Figure 3 of the drawings. It will be apparent that when a stack of labels containing labels of varying widths is inserted from the top into the magazine compartment 32, that the guide rods 34 will receive the saw kerfs 21, the saw kerfs and the guide rods forming interengaging guiding elements, this resulting in the proper superposed registration of each label in the stack. Furthermore, since the distance between any set of opposed rods 34 is equal to the distance between the bottoms of saw kerfs, it will be evident that the guide rods 34 will contact a portion of each label, irrespective of its width, this cooperation resulting in the centering of each label both transversely and longitudinally in the compartment 32.

The interengaging cooperation between the guide rods 34 and the cut out portions 21 of each label L affords a simple method for preventing multiple label feeding and for facilitating single label selection. To

this end each of the guiding elements 34 is provided at an end thereof with an overhanging lip or flange 35, shown in detail in Figure 5 of the drawings, this overhang being just sufficient for restraining label withdrawal from the stack in the magazine. Figure 4 of the drawings shows the manner in which the restraining lips 35 cooperate with the bottom label L of the stack. Since each of the labels has a portion about the excised portion in contact with the guide rods 34, the overhanging lip must cooperate with every label in the stack, irrespective of the dimensions of any one label. In this manner multiple label selection is avoided, the overhang being just sufficient to restrain label withdrawal activity while not preventing label selection altogether.

In Figures 6 and 7 I show the application of my registering method and means in a multiple label magazine as used for feeding a plurality of labels for application to a plurality of containers, as disclosed in the co-pending application of Jonathan Peterson, Serial No. 443,370, filed February 8, 1921. The magazine shown in Figure 6 comprises a plurality of compartments 32', each of the compartments being of similar configuration and having similarly spaced guiding rods 34', each of the guiding rods 34' being provided preferably at the bottom end thereof with the overhanging lips 35'. It will be apparent from Figure 7 that the labels L and L' in the successive label compartments will be substantially centered and registered, irrespective of the varying widths of the labels as shown in the said figure. The labels are adapted to be fed from the bottom, a suction picker 36 being preferably used for selecting the bottom label of each stack of labels. The suction picker comprises a suction chamber 37 and a plurality of picker elements 38, each element 38 having a suction port 39 opening into the suction chamber 37; the said suction port 39 being open at the concave face 40 of the suction element 38. The picker 36 is adapted to be reciprocated to and from the label magazine. When the said picker is in a position adjacent the magazine, the suction in the chamber 37 communicating with the ports 39 will be operative for removing the bottom label of each stack, the concave contour of each picker element 38 facilitating removal of the bottom label by permitting curling thereof, each of the overhanging lips 35' permitting a facility of selection of such bottom label while restraining the next succeeding label from being removed during such selecting operation. The picker mechanism forms no part of my present invention, as any means for selecting each of the labels from the stack may be used, such picker mechanism being here shown for purposes of illustration only. It will be ap-

parent that since each of the labels is properly centered in the magazine, that the picker mechanism 36 will remove each label in properly centered relation for further 5 label application operations.

In Figures 8 to 11 I have shown the method of label selection and application disclosed in the above mentioned copending application, Serial No. 443,370, this 10 method being here shown for illustrative purposes to further point out how the labels, after being removed in centered and registered relation, are registered with respect to packets or containers for proper registered application thereto. In Figure 8 is 15 shown the suction picker 36 referred to hereinbefore, a label L being shown on the picker after removal therefrom from the magazine compartment 32. As hereinbefore referred to this picker is adapted for reciprocating operation and when in descended position as shown in Figure 9, a horizontal reciprocating label remover 41 is moved in overlying relation with respect 20 to the picker 36; the said label remover 41 also being provided with a suction box 42 and a series of suction ports 43 adapted, when connected to an exhaust mechanism, to remove the label L from the picker 36 25 when the suction box 37 is opened to atmosphere. The label remover 41 is then moved out of overlying relation with respect to the picker 36 and moved into overlying relation with a series of movable belts 30 43', 43² and 43³, the label L being then deposited on the said movable belts. These belts are each provided with an adhesive coating, as shown, for example, in Figure 35 11 of the drawings, such adhesive coating being designated as 44' and 44³, the labels, after being deposited on the spaced belts 43', 43² and 43³, receiving on their under side a coating of adhesive from the said belts in 40 a manner as will be apparent. The spaced 45 belts convey the label to a label applying station, belt 43² before the label reaches the label applying station being moved out of contact relation with the label, as diagrammatically shown in Figure 10 of the drawings. At the label applying station a packet 50 or container C is moved upwardly into contact with the label L, the upward motion of this container effecting removal of the said label from the spaced belts; means (not 55 shown) being provided for applying the said label about the walls of the container C. After the feeding and labeling operations a labeled packet or container is obtained, as shown in perspective in Figure 60 12 of the drawings, it being particularly noted that the label will be produced in properly registered position on the lateral walls of the container, this resulting from the label centering operations and the feeding 65 of the said labels in such centered or

registered position. Although I have shown in detail one method of label selection and label application, it will be apparent that any other method or means for selecting the labels from the magazine and for applying 70 the labels to containers may be utilized, my invention comprehending the feeding of these labels into properly registered and centered position in the magazine and the feeding of these labels from the magazine 75 in such centered relation for registered label application.

The operation and use of my method and apparatus will, in the main, be apparent from the above description thereof. Each 80 label stack 20 is provided with a plurality of saw kerfs or milled portions by a milling machine, as shown in Figure 2, each label of each such stack being provided as a result of this operation with similar saw kerfs; 85 the superposed saw kerfs forming guiding channels for cooperation with similarly spaced guiding means 34 in the magazine compartment 32, this cooperation between the guiding channels and the guiding means 90 resulting in properly registered labels as regards width, length and height. The slight overhanging lips 35 in each of the guiding elements 34 provide means for effectively restraining multiple label removal and for 95 efficiently permitting single label selection. The centered and registered labels are then fed in such centered relation for registered label application to containers and packets.

It will be apparent from the above that 100 I have provided a method and means for feeding sheets in the form of labels so that such labels may be individually selected in an efficient manner from the label source or supply and so that the labels may be fed in 105 properly centered and registered position for application to packets or containers. It will be also apparent that although I have shown my method and apparatus as applied to label feeding, that such method and apparatus is applicable broadly to all sheet feeding where similar problems of sheet selection and registry are involved.

While I have shown my device in the preferred form, it will be obvious that many 115 changes and modifications may be made in the structure disclosed without departing from the spirit of the invention, defined in the following claims.

I claim:

1. A stack of labels comprising a series of individual labels of varying dimensions, the labels being provided with registering cut out portions in the edges thereof, the registering cut out portions defining a guide 120 channel means, the distance, in any one label, between the bottom of a cut out portion in a label edge and a predetermined point in an opposed label edge being less than the distance between the corresponding label 125 130

edges in a label of smallest dimensions in the stack.

2. A stack of labels comprising a series of individual labels of varying widths, the labels being provided with registering cut out portions in the edges thereof, the registering cut out portions defining a guide channel means, the distance in any one label, between the bottom of a cut out portion in a label edge and a predetermined point in an opposed label edge being less than the distance between the corresponding label edges in a label of smallest width in the stack.
- 15 3. A stack of labels comprising a series of individual labels of varying dimensions, the labels being provided with registering cut out portions in the edges thereof, the registering cut out portions defining a guide channel means, each label being provided with a plurality of cut out portions, the distance in any one label, between the bottom of a cut out portion in a label edge and a predetermined point in an opposed label edge being less than the distance between the corresponding label edges in a label of smallest dimensions in the stack.

4. A stack of labels comprising a series of individual labels of varying dimensions, the labels being each provided with a plurality of opposed cut out portions cooperating for label registration, the distance, in any one label, between the bottoms of opposed cut out portions being less than the distance between the corresponding label edges in the label of smallest dimensions in the stack.

5. A stack of sheets comprising series of superposed sheets of varying dimensions provided with registering cut out portions in the edges thereof, each sheet being provided with a plurality of cooperating cut out portions, the distance in each of the sheets of the series, between the bottoms of a similar pair of cooperating cut out portions being of a predetermined and constant length.

6. A sheet blank comprising a body portion having a given configuration or body outline and provided with cooperating excised portions in the edges thereof, the said excised portions being formed by taking the said blank having the given body outline and cutting into the body thereof, the distance between the bottoms of a pair of cooperating excised portions being of a predetermined length.

7. A label comprising a body portion having a given configuration or body outline and provided with a cut-out portion in an edge thereof adapted for registration of the label, the said cut-out portion being formed by taking the said label having the given body outline and cutting into the body thereof, the distance between the bottom of the

cut-out portion and a given point in an opposed edge of the label being of a predetermined length.

8. A label comprising a body portion having a given configuration or body outline and provided with a plurality of sets of cut-out portions spaced along different edges of the label and formed by taking the said label having the given body outline and cutting into the body thereof, the distance between the bottoms of a set of cut-out portions being of a predetermined length, the said set being adapted for label registration.

9. In combination, a supply magazine holding a stack of sheets or labels of varying dimensions, said magazine including guide means for the sheets, the sheets being provided with registering excised portions formed by cutting into the body of the sheets and defining a guide way or channel cooperating with the guide means, the distance between the bottom of an excised portion and a predetermined point in a label body being constant throughout the label stack.

10. In combination, a supply magazine holding a stack of sheets or labels of varying dimensions, said magazine including opposingly spaced guide means for the sheets, the sheets being provided with similarly spaced registering excised portions formed by cutting into the body of the sheets and defining guide ways cooperating with the guide means, the distance between the bottoms of spaced guide ways being constant throughout the sheet stack.

11. In combination, a supply magazine holding a stack of sheets or labels of varying dimensions, said magazine including inset guide rods disposed vertically in the magazine, the sheets being provided with registering excised portions formed by cutting into the body of the sheets and defining guide ways cooperating with the guide rods, the distance between the bottom of an excised portion and a predetermined point in a sheet being constant throughout the sheet stack.

12. In combination, a supply magazine holding a stack of sheets or labels of varying dimensions, said magazine including opposingly spaced guide means for the sheets, the sheets being provided with similarly spaced registering excised portions forming guide ways and cooperating with the guide means, the distance between the opposed guide means being less than the distance between opposite edges of any label in the stack.

13. In combination, a supply magazine holding a stack of sheets or labels of varying dimensions, said magazine including opposingly spaced guide means for the sheets, the sheets being provided with similarly spaced registering excised portions forming guide ways and cooperating with the guide

means, the distance in each of the sheets between bottoms of excised portions and the distance between the opposingly spaced guide means being of a predetermined and 5 constant length.

14. In combination, a supply magazine holding a stack of sheets or labels, said magazine including guide means for the sheets, the sheets being provided with registering excised portions forming a guide way or channel and cooperating with the guide means; the guide means being provided at one end thereof with a short overhang adapted to cooperate with each sheet at the excised 10 portion thereof to restrain withdrawal of the same from the magazine.

15. In combination, a supply magazine holding a stack of sheets or labels of varying dimensions, said magazine including opposingly spaced guide means for the sheets, the sheets being provided with similarly spaced registering excised portions forming guide ways and cooperating with the guide means, the distance between the opposed 15 guide means being less than the distance between opposite edges of any label in the stack; the guide means being each provided at an end thereof with a short overhang adapted to cooperate with each label at the excised 20 portion thereof to restrain withdrawal of the same from the magazine, the construction being such that a short overhang will suffice for cooperation with all labels irrespective of the variation in dimensions of such labels.

16. In the method of centering a series of superposed sheets or labels of varying widths or lengths, the step which consists in excising portions of the label edges 25 to a depth such that each of the labels may be contacted by a guiding element set into the guiding way formed by the superposed excised portions.

17. In the method of centering a series 30 of superposed sheets or labels of varying widths or lengths, the steps which consists in milling or sawing the superposed series of labels in opposed edges thereof to a depth such that each label irrespective of 35 width or length is provided with opposed excised portions.

18. In the method of centering a series 40 of superposed sheets or labels of varying widths or lengths, the steps which consist in milling or sawing the superposed series of labels in opposed edges thereof to a depth such that the distance between the bottoms of the excised portions in opposed 45 edges of each label will be of a predetermined constant value.

19. The method of centering a series 50 of superposed sheets or labels of varying widths, which consists in providing similar cut out portions in each of the labels, in 55 providing a magazine having guiding ele-

ments located at equal distances from a median line of the magazine and in positioning the series of superposed labels in the magazine, the excised label portions forming channels for receiving the guiding 60 elements.

20. The method of centering a series of superposed sheets or labels of varying widths, which consists in providing similarly opposed cut out portions in each of 65 the labels, in providing a magazine having guide rods located at equal distances from a median line of the magazine and in positioning the series of superposed labels in the magazine, the excised label portions 70 forming channels for receiving the guide rods.

21. In the method of feeding sheets or labels of varying widths or lengths into registering position on containers, comprising the steps of excising portions of each label so that the distance between the bottoms of the excised portions in each label is of a predetermined constant length, providing guiding elements spaced a distance 75 equal to such predetermined length, and feeding the labels between the guiding elements with the excised portions receiving the guiding elements, whereby each label is centered irrespective of its width or 80 length.

22. The method of feeding sheets or labels of varying widths or lengths into registering position on containers, comprising the steps of excising portions of each 85 label so that the distance between the bottoms of the excised portions in each label is of a predetermined constant length, providing guiding elements spaced a distance 90 equal to such predetermined length, feeding 95 the labels between the guiding elements with the excised portions receiving the guiding elements, whereby each label is centered irrespective of its width or length and in then feeding each centered label into registered 100 position for application to a container.

23. The method of feeding sheets or labels of varying widths or lengths into registering position, comprising similarly excising portions of each sheet to provide a body 105 portion in each sheet of predetermined and unvarying length, feeding the sheets at a sheet supply station with the said body portion centered between guiding elements and feeding the sheets successively from said 110 supply station in centered and registered position to a second station.

24. In the method of feeding sheets or labels of varying widths or lengths into registering position on containers for application thereto, comprising similarly excising portions of each sheet to provide a body portion in each sheet of predetermined and unvarying length, and feeding the sheets 115 at a sheet supply station with the said body 120 portion 125

130

portion centered between guiding elements whereby the sheets are centered for label registration.

25. In apparatus for feeding sheets of various widths or lengths from a supply magazine in which the sheets are selected one at a time by a picker mechanism and in which means are provided for restraining multiple sheet selection, the method of restraining multiple sheet selection while permitting ease of single sheet selection

which consists in similarly excising portions of each sheet such that each sheet irrespective of width or length is provided with such excised portions and in feeding such sheets through restraining elements located in the path of the excised portions of the sheets.

Signed at Chicago, in the county of Cook and State of Illinois, this 8th day of March 20 A. D. 1921.

JAMES C. THOM.
